UNITED STATES PATENT OFFICE.

EDOUARD E. NININ, OF PHILADELPHIA, PENNSYLVANIA.

HAIR-CUTTER.

1,302,835.

Specification of Letters Patent.

Patented May 6, 1919.

Application filed January 14, 1919. Serial No. 271,127.

To all whom it may concern:

Be it known that I, EDOUARD E. NININ, a citizen of France, residing at Philadelphia, in the county of Philadelphia and State of 5 Pennsylvania, have invented certain new and useful Improvements in Hair-Cutters, of which the following is a specification.

This invention relates to cutlery, and more especially to rotating knives; and the 10 object of the same is to produce a hand implement for cutting human hair.

One object of the invention is to provide means for driving the cutting reel by moving the implement over the head.

15 Another object is to adapt the device to the cutting of hair at the required length by setting a movable blade.

Another object is to provide this device with a comb, and means for keeping it in 20 alinement with said movable blade.

Another object is to provide means for readily replacing the blades in the reel when they become dull.

Other objects will be disclosed in the following specification and claims. Referring 25 to the drawings—

Figure 1 is a side elevation of this device partly broken away.

Fig. 2 is a section on the line 2—2 of 30 Fig. 1, and Fig. 3 is a section at right angles to the sectional line of Fig. 2.

The frame 1 is shaped in section as seen in Fig. 2, each pendant arm terminating in a head 2 which is practically round and each 35 arm above its head also having an upright slot 3, while the arch 4 connecting the arms may have a perforation 5 at its center. The edges of the arms may be connected by walls 6 to give strength to the parts and to produce 40 a substantially rectangular handle at the upper end of the frame, but these walls should terminate short of the working part of the device, and certainly they should leave the front of the frame open so access to the 45 reel, and the bottom of the frame open so that the hair can enter. This last opening is indicated at 7, and near it a cross bar 8 connects the heads if thought necessary.

Projecting outward from the center of 50 each head is a stub shaft 10 whose outer end may be held by a hanger 11 if desired, and on this shaft is rotatably mounted a main wheel 12 preferably having a rubber tire 13 projecting a little beyond the periphery 55 of the head and adapted to contact with the head of the person whose hair is being cut.

This wheel carries a ring 14 of internal gear teeth from which power is communicated through a train of gears to the reel herein-after described. While this may take any 60 desired form, I have herein shown it as consisting of pinions 15 fast on the ends of a shaft 16 which carries gears 17 meshing with pinions 18 fast on a counter shaft 19 located above said shaft 16 as perhaps best 65 seen in Fig. 2. The counter shaft 19 in turn carries gears 20 meshing with pinions 21 on the hub 22 of the reel which is mounted on the shaft 16. The latter may therefore be called the reel shaft, although it will be 70 understood that the reel is rotated thereon much more rapidly than does the shaft itself. As seen in Fig. 3, the reel shaft is disposed below the axis of the stub shafts 10, while the counter shaft 19 is above the same. 75 All the gears mentioned are of a size to be well contained within the peripheries of the round heads 2 of the frame or casing and to be protected to an extent by the end walls 6 as well as the side walls or arms of the 80 frame itself. In a simpler and cheaper type of the machine it might be possible to drive the reel by a train of gearing connected with one main wheel, and omit it at the other side; but I prefer to drive it from both main 85 wheels as shown and described. However, I do not wish to limit myself in this respect, nor as to the details of the train itself. The shafts 16 and 19 are rotatably mounted in the bearings within or carried by the heads 90 2, and the main shaft which extends through said heads carries the pinions 15 which receive their power from the gearing 14 in the main wheels 12.

The reel is herein shown as made up of 95 two pairs of arms 24 projecting from the hub 22, blades 25 laid against the contiguous faces of the arms of a pair, the right-angular washer 26 passing radially over a screw 27 and having arms lying against said 100 blades, and a rather heavy nut 28 threaded onto the screw 27 against the body of the washer so as to hold the same down upon the hub and at the same time cause its arms to clamp the two blades 25 against the two 105 arms 24 of the pair. The other pair of blades are held by another washer at the opposite side of the hub in the same way. However, it is obvious that there might be a greater number of reel arms and a corresponding alteration in the construction of 110 the washers, or in fact the details of the reel

itself might be varied considerably without departing from the spirit of the invention. As thus described, the nuts are accessible through the large front opening 29 in the frame or casing between the two heads, and when the nut has been removed and the washer removed or loosened, the blades can be withdrawn, replaced, adjusted or handled as may be necessary. I would make the nuts 5 rather heavy to give momentum to the reel when it is rotated by the train of gears described above, but even this suggestion may be disregarded if thought necessary. Manifestly the outer edges of the blades 10 must travel within a path which is truly cylindrical around the center of the shaft 16.

The other blade 35 is relatively fixed, although it is adjustable by means which will be described. Its cutting edge coacts with 15 the outer edges of the blades on the reel and stands in rear of the opening 7 through which the hair projects. Arms 30 rise from the ends of this blade and carry outstanding pins 31 which pass through slots 33 in the heads 2 of the casing, such slots being concentric with the axis of the reel itself. In addition, the ends of the blade travel on ribs 33, and the blade itself is curved transversely and slightly so as to fit accurately 20 against these ribs as it is adjusted toward and from the opening 7. Outside each head of the frame is a rock arm 36 pivotally mounted on the stub shaft 10 and having a slot 34 in its lower end to loosely receive 25 the pin 31 where the same projects beyond the head 2, and pivoted to the upper end of said arm above the stub shaft is a link 37 rising through the hanger 11 if the latter be employed. The upper ends of the links 30 are connected by means of a rod 38 slidably mounted in the slots 3 above referred to, and said rods may have knobs or buttons 35 on its extremities, or a single knob or handle 39 projecting through the opening 5 in the arch 4 of the frame, or both as shown in Fig. 2, the obvious purpose being 40 to give the operator means for adjusting the rod 38 vertically within the slots 3. Such adjustment swings the arms 36 whose slots 45 34 by engaging the pins 31 adjust the cutting edge of the blade 35 toward or from the opening 7.

The comb 45 has teeth 43 at its front edge projecting toward the opening 7, while arms 40 rise from the ends and have outstanding pins 41 also mounted in the slot 34 of the rocker arms 36. The body of the comb may be curved slightly as shown, and it is guided in a cut-out 42 around the edge of the heads 60 2, as best seen in Fig. 3. Therefore the comb moves when it is adjusted, around the center of the stub shafts 10 which of course is the center of the round heads. Adjustment is effected by the same means that adjusts the blade 35, and at the same time, and

therefore the comb and blade will move together. It is of course necessary that the blade should be adjusted accurately around the center of the reel, because its cutting edge coacts with the lower edges of the 70 blades 25 on said reel. But it will be seen that, as the blade is adjusted to the right in Fig. 3, the blade in being adjusted in the same direction recedes from the comb inward, whereas in the position of parts illustrated 75 these elements are practically in contact. The result will be that the hair will be cut longer when adjustment is effected, whereas with the parts standing in contact as shown, the hair would be cut quite short. 80

The operation of the device will be readily understood. Movement of the main wheels over the head of the person whose hair is being cut rotates the reel at a relatively high rate of speed, its blades 25 moving toward 85 the relatively fixed blade 35 and their edges coacting with the cutting edge thereof in the usual manner. Setting the parts as described will regulate the length of the haircut, and such setting is under the immediate 90 control of the operator. This is because the hair must be cut short at certain places on the head and longer elsewhere. While I have described this device as useful for cutting hair on the human head, it is quite obvious 95 that it could be employed in other ways, and I do not wish to be limited in that respect.

The foregoing description and the drawings have reference to what may be considered the preferred, or approved form of 100 my invention. It is to be understood that I may make such changes in construction and arrangement and combination of parts, materials, dimensions, et cetera, as may 105 prove expedient and fall within the scope of the appended claims.

Having thus fully described my invention what I claim as new and desire to secure by Letters Patent is:—

1. In a hair cutter, the combination with a reel carrying blades, a frame within which it is rotatably mounted, the frame having an opening for the hair and guides in its ends struck on curves around the axis of 115 said reel, and means for rotating the latter; of a blade movably mounted on said guides and with its cutting edge coacting with the outer edges of the blades in the reel, and means for adjusting said blade.

2. In a hair cutter, the combination with a reel carrying blades, a frame within which it is rotatably mounted, the frame having an opening for the hair and guides in its ends struck on curves around the axis of 125 said reel, and means for rotating the latter; of a blade curved slightly in its width and movably mounted at its extremities on said guides, its cutting edge coacting with the outer edge of the reel-blades, arms pivoted 130

within said frame and connected at their outer ends with said blade, and manually operable means for adjusting the inner ends of the arms, as described.

5 3. In a hair cutter, the combination with a reel carrying blades, a frame within which it is rotatably mounted, the frame having an opening for the hair and guides in its ends struck on curves around the axis of 70 said reel, and means for rotating the latter; of a blade curved slightly in its width and movably mounted at its extremities on said guides, its cutting edge coacting with the outer edge of the reel-blades, arms pivoted 75 within said frame and connected at their outer ends with said blade, links pivoted to the inner ends of said arms, a rod connecting the other ends of said links, the frame having slots within which said rod 80 moves, and knobs on said rod.

20 4. In a hair cutter, the combination with a reel carrying blades, a frame within which it is rotatably mounted, the frame having an opening for the hair and guides in its ends 85 struck on curves around the axis of said reel, and means for rotating the latter; of a blade curved slightly in its width and movably mounted at its extremities on said guides, its cutting edge coacting with the outer edge of the reel-blades, arms pivoted 90 within said frame and connected at their outer ends with said blade, links pivoted to said arms, a rod connecting said links, the frame having an opening in its arch, and a 95 knob on said rod projecting through said opening, for the purpose set forth.

25 5. In a hair cutter, the combination with a substantially U-shaped frame having round heads and an arched center, main 100 wheels pivotally mounted on said heads and projecting beyond their edges, a reel shaft journaled on said heads below the axis of said main wheels, a reel thereon, and a train of gears between the main wheels and the hub of the reel; of a blade carried by and between said heads and coacting with the blades in the reel, a comb also carried by and between said heads, means for adjusting the position of this blade around the 105 axis of said reel, and means for adjusting the position of the comb around the axis of said main wheels but maintaining it in radial alinement with said blade, for the purpose set forth.

30 6. In a hair cutter, the combination with a frame having round heads and an arch connecting them, stub shafts at the centers of said heads, main wheels mounted on said shafts, a reel shaft between the heads below 110 the stub shafts, and gearing between the main wheels and the hub of the reel; of guides within the heads, one pair around the reel shaft and the other around the stub shafts, a blade adjustable on the first pair 115 of guides, a comb adjustable on the second

pair of guides, and means for adjusting said blade and comb.

7. In a hair cutter, the combination with a frame having round heads and an arch connecting them, stub shafts at the centers of 70 said heads, main wheels mounted on said shafts, a reel shaft between the heads below the stub shafts, and gearing between the main wheels and the hub of the reel; of guides within the heads, one pair around the 75 reel shaft and the other around the stub shafts, a blade adjustable on the first pair of guides, a comb adjustable on the second pair of guides, pins projecting from the extremities of both the blade and the comb, 80 arms pivotally mounted on said heads and having slots whereof each engages two of said pins, and means for adjusting the position of said arms.

8. In a hair cutter, the combination with 85 a frame comprising round heads and an arch connecting them, a reel mounted on a shaft through the heads below the centers of the latter, guides within the heads around the reel shafts, guides also on the heads around 90 their peripheries, and means for rotating said reel; of a blade mounted on the first named pair of guides and having pins at its extremities, a comb mounted on the second named pair of guides and having pins 95 at its extremities, a pair of rocker arms pivoted at the centers of said heads and having slots whereof each engages two of said pins, and manually operable means for adjusting the upper end of said arms, for the purpose 100 set forth.

9. In a hair cutter, the combination with a frame comprising round heads and an arch connecting them, a reel mounted on a shaft through the heads below the centers of the 105 latter, guides within the heads around the reel shaft, and guides also on the heads around their peripheries, and means for rotating said reel; of a blade mounted on the first named pair of guides and having pins 110 at its extremities, a comb mounted on the second named pair of guides and having pins at its extremities, a pair of rocker arms pivoted at the centers of said heads and having slots whereof each engages two of 115 said pins, links pivoted to the upper ends of said arms, rods connected to the upper extremities of said links, and guides on the ends of the frame in which said rod moves.

10. In a hair cutter, the combination with 120 a frame having spaced heads substantially circular in outline, a shaft journaled in said heads below their centers, the heads having slots struck around the axis of said shaft and ribs paralleling said slots, a reel rotatably mounted on said shaft, and means for driving it; of a blade whose extremities are slidably mounted on said ribs, arms rising from said extremities, outstanding pins on said arms traveling in said slots, a comb 125 130

movably mounted around the edge of said heads and having upstanding arms at its extremities, outstanding pins on said arms, a pair of links pivoted on said heads and having slots, each engaging a pair of said pins whereby the blade and comb may be adjusted simultaneously, and means for adjusting the position of said arms.

11. A reel for hair cutters comprising a hub having arms disposed in pairs and a radial screw between the arms of each pair, blades adapted to lie against adjacent faces

of said arms, a washer whose body has an opening passing over said screw and is provided with arms adapted to lie against said blades, and a nut on the screw against said body. 15

In testimony whereof I affix my signature in presence of two witnesses.

EDOUARD E. NININ.
